UNITED STATES PATENT OFFICE.

PAUL THEODORE WALLGREN, OF CHICAGO, ILLINOIS.

WHEELED TOY VEHICLE.

Application filed October 24, 1927. Serial No. 228,465.

This invention relates to coaster toys of the so-called "scooter" type, and has for its object the provision of a wheel coaster toy of the "scooter" type of increased capacity, simple and sturdy construction, and a substantially increased factor of safety and utility.

A feature of the invention consists in the provision of a wheeled toy of this type having a platform provided with a box body 10 forwardly thereof, leaving a standing platform in its rear, with a stabilizing pair of wheels at the rear of the platform, a steering wheel and post at its front end, and a steering handle connected to the post and movable 15 from rearwardly inclined steering position to forwardly extended hauling position.

A further feature of the invention consists in a structurally advantageous form of steering handle and mount providing means for 20 adjustment of the propelling steering position to children of different sizes.

Other objects and features are discussed in the following detailed specification when read in conjunction with the accompanying 25 drawings forming part thereof, and in which:

Figure 1 is a perspective view of the wheeled toy with the handle in propelling steering position,

Figure 2 is a vertical sectional view through 30 the center of the forked steering post and handle, showing its pivotal mounting and swinging adjustment,

Figure 3 is a top plan view of the wheeled toy shown in Figure 1 with parts of the steering post and its pivotally connected platform hanger in section,

Figure 4 is a vertical section centrally of the vehicle as shown in Figure 3,

Figure 5 is a vertical section on an enlarged scale taken on the line 5—5 of Figure 4,

Figure 6 is a view illustrating the use of the wheeled toy with its handle in propelling steering position,

Figure 7 is a similar view showing the handle moved downwardly to coasting steering position, and

Figure 8 is a similar view showing the handle extending forwardly to hauling position.

Referring to the drawings by numerals, 1 designates a longitudinally extending platform mounting having at its forward end a box body 2 appropriately secured thereto, 55 leaving rearwardly thereof a standing plat-

form 3, upon which the feet of the user rest when propelling or coasting. At the rear end of the platform, a pair of spaced stabilizing wheels 5 are appropriately mounted at opposite sides, as by means of the axle 4 riveted or otherwise rigidly connected to the under side of the platform, and upon the opposite ends of which the wheels 5 are journaled.

The forward end of the platform 1 is itself supported by a hanger having lower spaced arms 6 of metal embracing and rigidly secured to opposite sides of the forward end of the platform, and having converging arms 7 uprising therefrom and embracing therebetween at their upper ends 8 the joined plates 70 9 of a tubular housing 10 for the pivot or king bolt 11.

A front steering wheel 12 is disposed centrally forwardly of the platform 1, and is journaled between the lower forked ends 13 75 of a steering post or frame, the upper end of which is closed by the cross bar 14. Between the wheel 12 and the cross bar 14, stands a bracket plate 15, having rearwardly extending, vertically aligned ears 16 and being secured between the forked sides of the steering post or frame, as by means of forwardly offset pairs of ears 17 riveted to the spaced bars 13. The aligned ears 16 are spaced apart the proper distance to embrace the tubular 80 housing 16, and permit the bolt 11 to extend therethrough and be appropriately held therein as by a cotter pin, or other suitable means.

The steering post is turned about the axis 90 formed by the bolt or king pin 11 through a forked steering handle 18, the spaced bars of which converge to their outer ends and are appropriately secured to the steering bar 19 of the handle. At their lower ends, the forks 95 of the handle 18 embrace the upper portion of the forked bars 13 above the wheel, and are pivotally connected to said bars, as at 20, this pivot point being located below the point of the pivotal interconnection between the steering post and the platform supporting hanger. The cross bar 14 joins the upper ends of the forks 13 of the steering post, and has secured thereto a rearwardly curving detent plate 21 having a plurality of locking apertures 22 therein. Cooperating with this detent plate is a plunger 23 extending through vertically aligned openings in a bracket plate 24, riveted or otherwise attached to the inner faces of the forked sides of the handle 18 105 110

above the detent plate. A coiled spring is mounted on the plunger between the upper end of the bracket 24 and a collar 25 on the plunger, and normally tends to project its 5 lower end downwardly into engagement with the detent plate. The upper end of the plunger is offset, as at 26, to form a lifting finger by means of which the plunger may be lifted from engagement with the detent plate.

10 The plurality of apertures 22 are intended to position the steering handle 18 at different angles rearwardly inclined relatively to the platform, so that the cross bar 19 of the handle may be positioned at different heights, 15 and at distances from the rear end of the toy to adapt the use of the toy to children of different sizes. The positions of the handle, as determined by the detent plate, represent what may be termed the propelling steering 20 positions, as suggested by the figure of the user in Figure 6 of the drawings. The handle, however, may be released from the detent and moved rearwardly and downwardly to what may be termed a coasting position, 25 as shown in Figure 7, or when practical use is to be made of the box body 2 for hauling ice, groceries, etc., the handle may be freed from the detent plate, and swung forwardly to a forwardly extended hauling position, as 30 suggested by Figure 8 of the drawings. When moved from either the rearward coasting position or the forward hauling position toward the intermediate propelling steering position, the lower end of the plunger 23 will 35 engage the curved edge of the detent plate and ride upwardly thereover to interlock with the desired opening 22 in the detent plate. Selection of the opening is, of course, controlled by the manual lifting of the finger 40 piece 26 until the plunger reaches the opening 22 giving the desired adjustment of the handle.

From the foregoing it will be evident that I have provided a wheeled toy of the so-called "scooter" type, which, in addition to the advantage of a toy of this type, provides 45 also the utilitarian feature of a small wagon or conveyance, the steering means being so

constructed as to provide for either hauling from a forward position as a conveyance, or 50 steering from a rearwardly inclined position as a scooter. The box body 2 may be utilized for carrying various articles, or may form 55 a seat for a small passenger. The hanger supporting the forward end of the platform from the front wheel steering post is of flat metal and adequate to stand the strains of rough usage. The arms 6 of this hanger preferably extend a substantial distance rearwardly from the front end of the platform, 60 so that support is adequately distributed. It will be further noted that the steering post and pivot pin 11 are tilted rearwardly, thus providing ease of steering.

The construction described and disclosed 65 herein represents, it is true, a preferred embodiment of the invention, but it is intended that it be illustrative rather than restrictive of the invention, since various structural changes and adaptations may be made within the spirit of the invention and the scope of the appended claim.

What I claim, therefore, and desire to secure by Letters Patent is:

In a wheeled toy having a low hung longitudinally extending platform mounting, and a box body at the forward end thereof, the combination of a pair of stabilizing wheels at the rear end of the platform, a hanger for the front end of the platform, a front wheel having a forked mount pivotally connected to the hanger and constituting a steering post, said forked mount including a pair of spaced bars, and an arcuately shaped plate secured to the upper end of said bars, 85 the plate being provided with perforations and extending rearwardly and over the pivotal mounting, a handle consisting of a pair of spaced bars pivotally connected to the bars of the forked mount, at a point below the 90 pivotal connection between the hanger and the forked mount, a spring pressed pin adapted to engage a perforation for locking the handle in a predetermined position.

PAUL THEODORE WALLGREN.
